UNITED STATES PATENT OFFICE.

JAMES L. WARNER, OF GIRARD, KANSAS.

VIOLIN PIANO.

1,409,322.

Specification of Letters Patent. Patented Mar. 14, 1922.

Application filed March 26, 1920. Serial No. 369,046.

To all whom it may concern:

Be it known that I, JAMES L. WARNER, a citizen of the United States, residing at Girard, in the county of Crawford and 5 State of Kansas, have invented a new and useful Violin Piano, of which the following is a specification.

This invention relates to violin pianos and is designed more especially as an improvement upon the structure shown for example in Patent No. 1,265,147 issued to me on May 7, 1918, and in Patent No. 1,309,004, issued to me on July 8, 1919.

One of the objects of the invention is to 15 simplify the mechanism of the apparatus so that it will not readily get out of order.

A further object is to provide mechanism whereby the instrument can be played by hand or by a pneumatic means, it being 20 possible to produce a delicate shading of the tones from fortissimo to pianissimo.

A still further object is to provide simple means for producing a tremolo or vibratory effect at will and for sounding harmonics.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a view partly in section and 40 partly in elevation of a portion of a piano showing the general arrangement of the parts constituting the present invention.

Figure 2 is an enlarged view partly in section and partly in elevation showing the 45 upper and lower belts employed for operating the bowing disks.

Figure 3 is a face view of the lapping portions of said operating belts.

Figure 4 is a plan view showing the 50 relative positions of certain of the bowing disks, buffers and their operating belts.

Figure 5 is an elevation of the power transmitting wheels.

Figure 6 is a detail of the mechanism 55 employed for producing harmonic tones.

Figure 7 is a view showing the tilttable

rail in section and shifted out of the position shown in Figure 1 to raise the levers connected thereto.

Figure 8 is a section through one of the 60 bowing elements.

Referring to the figures by characters of reference 1 designates the sounding board of the instrument, there being arranged at opposite sides of this board string plates 2 and 3 properly spaced from the sounding board. Mounted on the string plate 2 are the strings 4 adapted to be sounded by the hammers 5 which are operated by any suitable mechanism from the key board, one 70 of the keys being shown at 6. The hammer operating mechanism has been indicated generally at 7 and includes a wippen 8, a damper lever 9, a damper 10, etc. A pneumatic, indicated at 10', is provided for each 75 wippen and is to be operated in the same manner as the pneumatic of an ordinary player piano. It has not been deemed necessary to show this mechanism in detail. The parts heretofore described, with 80 the exception of the sound board interposed between two string plates, can be found in any ordinary player piano. The present invention consists of the addition of strings to be sounded for producing the 85 tones of a violin, there being improved mechanism for sounding said strings, said mechanism being operated either from the key board or by the pneumatic of the player mechanism, mechanism for damping the strings of the violin mechanism by the operation of the damper of the hammer mechanism, and means for engaging the strings to shorten the vibratory portions thereof thereby to produce harmonic tones. 95

The invention also resides in the addition of means for setting up a tremolo or vibratory effect simulating that of an ordinary violin.

The instrument is provided, at a point 100 above the wippens, with a support 11 on which a rail 12 is tiltably mounted, this rail being provided with an arm 13 connected, by a rod 14, to a crank arm 15 formed at the back end of a rod 16. Said 105 rod is mounted to slide and rotate within bearings 17 provided therefor below the key board and a knob 18 is preferably arranged at the front end of the rod where it can be conveniently reached by the performer. A brake disk 19 is fixedly mounted on one of the bearings 17 and another

brake disk 20 is fixedly mounted on the rod 16. A spring 21 which is attached to the rod and to the piano structures serves to draw the rod 16 longitudinally so as to hold the two brake members normally in contact, thereby to prevent accidental rotation of the rod 16. It will be obvious that, by pulling forwardly on the knob 18 the two brake members 19 and 20 may be 10 disengaged whereupon the rod can be rotated to swing arm 15 and cause the rail 12 to be tilted in either direction desired. When the rail has been brought to the position wanted the knob 18 can be released and the spring 21 will press the brake members 19 and 20 together so as to hold the parts in the position to which they have been adjusted. Another arm 22 is extended from the rail 12 and is connected by a spring 23 to a stationary rail 24, this spring serving to hold the rail 12 normally in a predetermined position.

Pivotedly mounted on suitable connecting members 25 on the rail 12 are outstanding 25 levers 26 the lower end of each lever being connected to one end of the wippen 8 by an arcuate wire 27. The upper end of each lever has a screw 28 mounted therein and provided with a contact button 29. Each 30 button is designed to bear against the upturned end 30 of a rod 31, said upturned end being connected to the lower end of a leaf spring 32 extending downwardly from a rail 33 and serving normally to hold the rod 31 35 pressed against the button 29. The back end of each rod is offset as indicated at 34, the successive rods being offset upwardly and downwardly respectively. Each of these rods 34 has a smaller rod 35 adjustably connected thereto by a set screw 36 or the like, as shown, there being a leaf spring 37 at the 40 back end of each rod 35 to which is attached a yoke 38. Each of the rods 35 passes through an opening in the sounding board 1, one of 45 these openings being indicated at 39. Thus the yoke 38 is supported between strings 40 which are mounted on the violin string plates 3 at the back of the sounding board. Each yoke 38 carries a spindle 41 on which is 50 secured a bowing device 42 consisting of a strip of material disposed at an acute angle to the axis of rotation of the spindle 41 and wound spirally about the spindle. By thus disposing the bowing element in a spiral, the 55 edge thereof wears evenly upon all portions of the wire or string 40 opposite the bowing device and the wear is not confined to any separate points as where the bowing edges are formed by separate superposed disks and 60 mounted for rotation in parallel planes.

As before stated the bowing devices extend between the violin strings 40 and are adapted to contact therewith, thereby to cause the strings to vibrate toward and from the 65 sounding board so as to produce the maxi-

mum volume of sound, it having been found by experiment that where a flat sounding board is used it is necessary, in order to produce the best tone, to vibrate along lines as nearly perpendicular to the sounding board 70 as possible.

Arranged back of the middle portion of the sounding board is a tubular shaft 43 extending upwardly from a friction disk 44. To the upper end of this tubular shaft is secured a pulley 45 on which is mounted an endless belt 46 which extends back of the shorter strings on the back of the sounding board and around a suitably supported pulley 47 located back of one end of the sounding board. Another shaft 48 is mounted for rotation within the shaft 43 and has a pulley 49 on the upper portion thereof which engages the upper belt 50 extending back of the longer violin strings 40 and mounted on a suitable support. Guide pulleys 51 are arranged back of the other end portion of the sounding board. Those bowing devices carried by the upwardly offset rods 34 are adapted to be pressed against and to be operated by the upper belt 50 while the bowing devices carried by the downwardly offset rods 34 are adapted to move against and to be operated by the lower belt 46.

Arranged back of the sounding board is a 95 stationary rail 52 having upwardly extending flexible supports 53 at desired points and on the upper ends of which is secured a movable rail 54. This rail has brackets 55 supporting upper and lower bars 56 to which are 100 secured yokes 57 and each yoke carries a backing or buffer roller 58, one of these rollers being arranged directly opposite each of the bowing devices so that one flight of the belt will pass between the rollers 58 and their 105 respective bowing devices. This arrangement of parts has been indicated clearly in Figures 2 and 4.

An arm 59 is extended upwardly from the 110 movable rail 54 and is connected by a link 60 to one arm of a bell crank lever 61. The other arm of this bell crank lever is connected by a wire 62 to a link 63 connected to a rivet pin 64 on a disk 65. This disk is journaled on an arm 66 mounted to swing upwardly and downwardly and which is adapted to be actuated by a link 67 connected to a bell crank lever 68. This lever can be operated by any suitable mechanism not shown and by means thereof the disk 65 can be moved 115 downwardly into contact with a friction wheel 69 mounted on a shaft 70. On this shaft is also mounted a friction disk 71 engaging the disk 44 and another friction disk 72 engaging a disk 73 which is secured to 120 the shaft 48. Motion is transmitted to the shaft 70 and the disk thereon through a belt 74 engaging a pulley 75 on the shaft, this shaft being driven by a pulley 76 operated by 125 a motor not shown.

It will be obvious that while the bowing devices are being rotated by the belts 46 and 50 the disk 65 can be brought down into contact with the disk 69 so as to be driven thereby. This will cause the wire 62 to be moved downwardly and upwardly, thereby oscillating the lever 61 and causing the rail 54 to move back and forth with its flexible support 53. This will cause the rollers 58 to move 10 toward and away from the belt so as to thrust the belt intermittently against the bowing devices with the result that said devices will be driven intermittently, thus to produce a tremolo or vibratory effect.

It is to be understood of course that when the shaft 70 is in operation motion will be transmitted through the disks 71 and 72 to the disks 44 and 73 respectively so that the shafts 43 and 48 will be operated and the two 20 belts 46 and 50 driven to actuate the bowing devices. It is necessary that the bowing devices engaging the short strings be driven at a higher speed than those engaging the long strings in order to produce the best 25 results because the vibrations of strings vary according to their length and gauge. The long strings will produce better sounds when vibrated by a slowly moving bowing device while a rapidly rotating bowing device will produce better results on a rapidly 30 vibrating short string.

A stationary rail 77 is mounted adjacent the violin strings 40 and carries depending leaf springs 78 each of which has a damper 35 79 for engaging one of the strings 40. Each damper is provided with a wire 80 extending to but disconnected from the corresponding damper 10 of the hammer mechanism, these connections 80 extending through openings 40 81 in the sounding board 1. Thus it will be seen that each time one of the dampers 10 is actuated by the hammer mechanism, the connection 80 will be actuated by the pressure thereagainst of a button 80' on the hammer 45 10, thus forcing the spring 78 of the damper 79 to yield as said damper moves against the violin string in the path thereof so as to stop its vibration.

It will be understood of course that each 50 time one of the keys 6 is depressed in the usual manner, and as shown in Figure 1, motion will be transmitted through the wippons 8 and wire 27 to the lever 26 which will thus be swung upon its fulcrum and 55 caused to press, at its upper end, through the button 29 against the rod 31 in the path thereof. This will force said rod longitudinally against the action of the spring 32 so as to bring the bowing device, which is connected to said rod, against the string in the path thereof and also against the moving belt. Accordingly the bowing device will be rotated by the belt and at the same time will wipe on the string so as to produce the 60 necessary vibration. By turning the rod 16

the levers 26 can be raised or lowered, thus to vary the amount of movement imparted to the rod 31 and correspondingly regulate the volume of sound produced. A tremolo effect can be produced by swinging the arm 70 15 back and forth rapidly thus to rapidly vary the stroke of each lever 26. The button 29 can, obviously, be completely withdrawn from engagement with the rod 31 so that the violin mechanism will not be operated 75 during the operation of the hammers 5.

For the purpose of producing harmonic tones a bar 82 is slidably mounted adjacent the strings 40 and carries a series of pins 83 each of which has a head 84 adapted to move 80 against one of the strings 40. A spring 85 is connected to one end of this bar and serves to hold the heads 84 normally out of contact with the strings 40. A bell crank lever 86 is connected to the bar and is adapted to be 85 operated by suitable mechanism, not shown. Thus when the bar is shifted against the action of spring 85 the heads 84 will come into contact with the strings so that when they are sounded the sound produced will 90 be at a predetermined interval above the normal tones produced by the strings.

What is claimed is:

1. In a violin piano the combination with a string, of an endless belt, a bowing element 95 carrying a spiral string engaging edge, and means for shifting said element simultaneously against the belt and string.

2. In a violin piano the combination with a string and a continuously moving belt 100 adjacent thereto, of a rod, a yoke carried thereby, a bowing device mounted for rotation in the yoke, yielding means for holding the yoke pressed laterally relative to the rod, yielding means for holding the rod out of 105 contact with the string and belt, a key operated lever for shifting the rod to move the bowing device against the string and belt, and means under the control of the operator for varying the movement of the rod under 110 the action of the lever.

3. In a violin piano the combination with a string and a continuously moving belt adjacent thereto, of a revoluble bowing device, a longitudinally movable supporting device 115 therefor, said device having a resilient laterally flexible portion adjacent the bowing device, spring means supporting said device and holding the bowing device normally retracted out of engagement with the string 120 and belt, a key actuated lever, adjustable means for transmitting motion therefrom to the supporting device, and means for shifting the lever to vary the movement of the supporting device under the action of the 125 lever.

4. In a violin piano a string, a continuously moving belt adjacent thereto, a bowing device, a longitudinally movable support therefor having a resilient portion for 130

- holding the supported device normally in position with the bowing device out of contact with the belt and string, a key actuated lever for shifting the supporting device to position the bowing device against the string and belt, a tiltable rail constituting a support for the lever, and means under the control of the operator for tilting said rail to raise or lower the lever and vary the movement of the supporting device under the action of the lever.
5. In a violin piano a string, a continuously moving belt, a bowing element, key operated means for shifting the bowing element into contact with the string and belt, a roller contacting with the belt at a point opposite the bowing element, and means for automatically reciprocating the roller to intermittently vary the pressure of the belt upon the bowing element.
10. In a violin piano the combination with a string, a bowing element, a movable belt, and key operated means for shifting the bowing element against the string and belt to rotate said element and sound the string, of a roller engaging the belt directly opposite the bowing element, an oscillating support for said roller, and power operated means for oscillating said support to vary the pressure of the belt upon the bowing element.
15. In a violin piano the combination with a string, a drive belt, a bowing element, key operated means for shifting the bowing element into contact with the string and belt, a roller contacting with the belt at a point opposite the bowing element, and means for automatically reciprocating the roller to intermittently vary the pressure of the belt upon the bowing element.
20. In a violin piano a bowing element comprising a spindle and a strip of material wound spirally about the spindle to present a spiral bowing edge.
25. In a violin piano a bowing element including a spirally wound strip of material each convolution of which is inclined relative to the axis of rotation.
30. In a violin piano the combination with a string and a drive belt adjacent thereto, of a rod, a yoke at one end of the rod, a bowing element carried by the yoke, a spring supporting one end of the rod and constituting means for holding the bowing element normally out of contact with the belt and string, and key operated means for shifting the rod against the action of the spring to bring the bowing element into contact with the string and the belt.
35. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
40. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
45. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
50. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
55. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
60. In a violin piano, a string, a drive belt, a longitudinally movable supporting rod, a bowing element carried thereby, yielding means for holding the rod normally in a predetermined position, a key operated lever for shifting the rod to move the bowing element into contact with the string and belt, a tiltable rail constituting a support for the lever, and means for tilting said rail to vary the movement of the rod by the lever, said means including a slideable and revolute rod, an arm thereon, means for transmitting motion from the arm to the rail, a stationary brake member, a brake member upon the rod, and yielding means connected to the rod for holding the brake members normally in contact.
65. In a violin piano a bowing element comprising a spindle and a strip of material wound spirally about the spindle to present a spiral bowing edge.
70. In a violin piano a bowing element including a spirally wound strip of material each convolution of which is inclined relative to the axis of rotation.
75. In a violin piano the combination with a string and a drive belt adjacent thereto, of a rod, a yoke at one end of the rod, a bowing element carried by the yoke, a spring supporting one end of the rod and constituting means for holding the bowing element normally out of contact with the belt and string, and key operated means for shifting the rod against the action of the spring to bring the bowing element into contact with the string and the belt.
80. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
85. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
90. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
95. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
100. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
105. In a violin piano the combination with a string, a belt adjacent thereto, a yielding supported rod, and a bowing element carried by the rod, of a tiltable rail, a lever fulcrumed thereon, adjustable means carried by the lever for engagement with the rod, a spring for holding the rail and lever normally in a predetermined position, a key-operated hammer-action including a wippen, and a connection between said wippen and the lever.
110. In testimony that I claim the foregoing as my own, I have hereto affixed my signature in the presence of two witnesses.

JAMES L. WARNER.
